UNITED STATES PATENT OFFICE

2,479,707

FREE-PLAY CONTROL CIRCUIT FOR
AMUSEMENT GAMESLyndon A. Durant, Chicago, Ill., assignor to Royal
Patent Corporation

Application May 7, 1948, Serial No. 25,744

1 Claim. (Cl. 273—121)

1

This invention relates to a free-play control circuit for amusement game and has for its principal object the provision of an improved construction of this character which will be highly efficient in use and economical in manufacture.

One of the objects of this invention is to provide in an amusement apparatus an electromagnetic ball-blocking means controlled either by a coin-controlled switch or by a circuit in which there is a hand-operated push button whereby the game apparatus may be initially conditioned by the operation of the coin-controlled switch and thereafter conditioned for replay under certain conditions by the mere operation of a hand-operated push button.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary perspective view of an amusement game apparatus in which my invention is incorporated;

Fig. 2 is a fragmentary sectional detail view taken substantially on line 2—2 of Fig. 1;

Fig. 3 is a perspective view of the ball-blocking means with parts thereof in extended relation with respect to each other;

Fig. 4 is a fragmentary sectional detail view similar to Fig. 2, but showing the parts thereof in different positions; and

Fig. 5 is a schematic diagram of the electric circuit embodied in the invention.

The drawings illustrate the preferred form of construction by which the several objects of my invention are accomplished.

The amusement game apparatus illustrated in Fig. 1, except as hereinafter pointed out, is of the conventional type. It includes a cabinet 10 having an inclined playboard 11 down which balls, projected by a projector 12 to the upper end of the board, are adapted to gravitate. This amusement game apparatus further includes a ball outlet pocket 13 in which spent balls are confined until released by movement in a conventional manner of a ball releasing bar 14. This bar 14 constitutes no part of the present invention and is of a well-known and conventional type.

Balls from the ball outlet 13 drop onto a track 15 which guides the gravitating rolling balls to an elevating means (not shown). This elevating means raises the balls from the track 15 through an opening 16 to a position indicated at 17, before

5 the projector 12. From this position the balls are projected through the runway 18 to the upper end portion of the board 11 from whence the balls are adapted to gravitate downwardly toward the lower end of the board into the outlet opening 13.

In the conventional amusement game apparatus there is mounted upon this board 11 one or more target switches hereinafter identified as 12 and 16. These switches control an electric score registering circuit of a well-known type and now commonly in use. This circuit constitutes no part of the present invention and is therefore not illustrated.

To carry my invention into effect I provide a ball blocking device indicated generally at 19. This blocking device more fully disclosed and claimed in my copending application, Serial No. 25,743, includes a bracket 20 secured to the underside of the board 11 as at 21. This bracket 20 carries an electromagnetic coil 22, the bore of which is disposed in alignment with an opening 23 formed in the board.

A U-shaped yoke is indicated at 24 and includes a finger 25 and an arm portion 26. The arm portion 26 extends through the opening 23 into the bore 27 of the coil 22 and is connected to a solenoid plunger 28. The yoke 24 is formed of non-magnetically attractive material, while the plunger 28 is formed of the usual magnetically attractive material.

30 The finger 25 extends through an opening 29 formed in the board 11 in spaced parallel relation with the opening 23. The lower end portion 30 of this finger 25 projects into a position with respect to the track 15 where balls 31 will be blocked from rolling down this track 15 to a position to be elevated through the opening 16 onto the runway 18.

The plunger 28 normally rests upon a spring leaf 32 of a switch unit 33. This switch unit 33 is carried by a bracket 34 secured to the underside of the board 11 as at 35 by means of wood screws or the like.

In Fig. 5 I have illustrated a circuit control for the ball-blocking device 19.

In this connection a power unit comprising a transformer is indicated at 39. The secondary side 37 of this transformer has connection with the main conductors 38 and 38'.

50 In this circuit is a relay switch 39, one side 40 of which is connected by a conductor 41 to the main conductor 38. The other side of this relay switch is connected by a conductor 41' to one side of the game conditioning circuit 42. The other side of the game conditioning circuit 42

is connected by a conductor 43 to the main conductor 38'. This game conditioning circuit is of a well-known construction and includes a free-play step-up unit 44. The relay switch 39 is controlled by the electromagnetic coil 45. One side of this coil 45 is connected by conductor 46' to one of the switch contacts 46 of the switch unit 33. The other side of this coil 45 has connection with one side 47 of a switch 48 by means of a conductor 49. The spring leaf 32 of the switch unit 33 is connected by a conductor 49' to the main conductor 38. The other side 50 of the switch 48 is connected to the conductor 38' by a conductor 51.

The switch 48 is adapted to be controlled by a coin slide 52 which includes a slide bar 53. When a proper coin is inserted in the coin slide 52, the slide bar 53 is released for movement to close the switch 48. Closing of this switch 48 will complete a circuit to the coil 45 through the conductors 51, 49, 46' and 49'. When this coil 45 is energized, the switch 39 is closed to complete the circuit to the game conditioning circuit 42, whereby the game is conditioned for play.

A relay switch is indicated at 54. One side 55 of this switch 54 is connected by a conductor 56 to a switch contact 57 of the switch unit 33. The other side 58 of the switch 54 is connected by conductor 59 to the conductor 38. The conductor 56 is connected to one side of the coil 22 by conductor 60. The other side of this coil 22 is connected by conductor 61 to one side 62 of a relay switch 63. The other side of this switch 63 is connected by conductor 64 to the conductor 38'. The switch 54 is controlled by a magnetic coil 65. One side of this coil 65 is connected by the conductor 66 to the conductor 38. The other side of this coil 65 is connected by the conductor 67 to the conductor 49 between the coil 45 and the side 47 of the switch 48.

The switch 63 is controlled by the electromagnetic coil 68. One side of this coil is connected by conductor 69 to the conductor 38. The other side is connected to a switch contact 70 of a ball-actuated switch 72 by conductor 71. The other side of this ball-actuated switch 72 is connected by conductor 73 to the conductor 38'. This ball-actuated switch is constructed and operates substantially the same as that disclosed in U. S. Patent No. 2,184,868.

The conductor 71 has connection by a branch conductor 74 to one side 75 of a ball roll-over switch 76. The other side of this switch 76 is connected by conductor 77 to conductor 38'. This roll-over switch is of a well-known type and may be of the structure shown in U. S. Patent No. 2,212,097.

An anti-tilt switch is indicated at 78. One side 79 of this switch is connected by conductor 80 to the conductor 71. The other side of this switch is connected by conductor 81 to the conductor 38'.

The arrangement is such that upon energization of the electromagnetic coil 45, the coil 65 will be simultaneously energized therewith, the latter to close the switch 54, whereupon a circuit will be set up to energize the coil 22. Upon energization of this coil 22, the ball-blocking yoke 24 will be elevated to move the finger 25 from ball-blocking position, permitting the balls 31 to roll down the track 15. This movement of the yoke 24 will break contact between the switch contacts 32 and 46 and make contact between the switch contacts 32 and 57, thereby connecting the coil 22 directly in circuit with the conductors 38 75

and 38' through conductors 49', 60, 61 and 64. While thus in circuit, the coil 22 will effectively hold the yoke 24 from ball-blocking position.

As soon as either of the switches 72 or 76 is closed by action of a ball rolling down the board 11 (of which switches there may be and generally are several mounted on the playboard 11), the coil 68 will become energized to open the switch 63, thereupon to deenergize the coil 22, permitting the yoke 24 to drop into ball-blocking position and again bringing into contact the switch contacts 32 and 46. The yoke 24 remains in this position until the switch 48 is again closed by the slide 53 whereupon the foregoing operation is repeated.

As heretofore pointed out, the game conditioning circuit includes a free-play step-up unit 44, which includes the ratchet 82. This free-play unit is of a well-known construction, and for further information as to its operation reference may be had to U. S. Patent No. 2,281,262. This ratchet wheel 82 carries a pin 83 which, when the game apparatus is not conditioned for a free-play, engages one side 84 of a switch 85 to hold the switch in open position. This side 84 of the switch 85 is connected by conductor 86 to the conductor 38'. The other side of this switch 85 is connected by conductor 87 to one side 88 of a push button switch 89. The other side of this push button switch 89 is connected by conductor 90 to the conductor 49 between the coil 45 and the side 47 of the switch 48.

When the game apparatus is conditioned for a free play in a manner well-known in the art, the ratchet wheel 82 will be moved in the direction of the arrow, Fig. 5, thus moving the pin 83 from engagement with the side 84 of the switch 85, permitting the switch 85 to be closed. A circuit will then be set up so that the coil 45 may be energized by merely closing the push button switch 89. In other words, when this condition exists, the game may be conditioned for a free play without employment of a coin and without the necessity of operating the coin slide 53.

From the foregoing description taken in conjunction with the accompanying drawings, it will be apparent that I have provided in an amusement game apparatus a circuit for controlling the conditioning of the apparatus for play, first, by the operation of a coin slide and thereafter, under certain conditions, by the operation of a hand-operated push button. It will be understood that these certain conditions will be effective only whenever the game apparatus is conditioned for giving a free play, which is accomplished in a manner well-known in the art by the player obtaining a certain score.

In the event that the game apparatus is tilted, the anti-tilt switch 78 will be closed, thereby to energize the coil 68 and to deenergize the coil 22 by the opening of the switch 63. This deenergization of the coil 22 permits the ball-blocking member 24 to automatically drop into ball-blocking position and to condition the game apparatus for further play only upon another operation of either the coin slide switch 48 or push button switch 89.

While I have illustrated and described the preferred form of construction for carrying my invention into effect, this is capable of variation and modification without departing from the spirit of the invention. I, therefore, do not wish to be limited to the precise details of construction set forth but desire to avail myself of such variations

and modifications as come within the scope of the appended claim.

Having thus described my invention, what I claim as new and desire to protect by Letters Patent is:

A game apparatus having a surface over which balls are adapted to roll comprising a game apparatus conditioning circuit which upon completion is adapted to condition the game apparatus for play, a normally open switch and an actuating coil therefor for completing the circuit, a ball blocking device for balls rolling over said surface and an actuating coil therefor, said device normally blocking movement of a ball, a normally open switch and a coil therefor to energize the coil of said blocking device, a normally closed switch and an actuating coil therefor for completing a circuit between said blocking device coil and a power source, said normally closed switch being in series circuit with the normally open switch and adapted when opened by its actuating coil to deenergize the blocking device coil, ball-actuated hazard switch means adapted to be engaged and actuated by balls rolling over said surface for energizing the coil of said normally closed switch to deenergize the blocking device coil, a coin-controlled circuit for simultaneously energizing said first-mentioned actuating coil and the

coil of said last-mentioned normally open switch for simultaneously energizing said conditioning circuit and the blocking device coil for the playing of the game, a push button switch controlled circuit for simultaneously energizing said first-mentioned coil and the coil of said last-mentioned normally open switch independently of the coin-controlled circuit, free-play means in said game conditioning circuit, a normally open switch in said push button circuit adapted when closed to condition said push button circuit for subsequent completion by operation of the push button switch, and means responsive to the operation of said free play means for closing said normally open switch of said push button circuit.

LYNDON A. DURANT.
